DESIGN FOR A FLY SWATTER

Herbert Jahn, Garfield, and Chester S. Zaremba,
Paterson, N. J., assignors to Cascade Plastics
Inc., a corporation of New Jersey

Application April 26, 1947, Serial No. 138,620

Term of patent 14 years

(Cl. D31—3)

To all whom it may concern:

Be it known that we, Herbert Jahn and Chester S. Zaremba, citizens of the United States, residing at Garfield and Paterson, in the counties of Bergen and Passaic, respectively, and State of New Jersey, have invented a new, original, and ornamental Design for Fly Swatters, of which the following is a specification, reference being had to the accompanying drawing, forming part thereof, wherein

Figure 1 is a perspective view of a fly swatter, showing our new design;

Figure 2 is a top plan view thereof;

Figure 3 is a side elevation; and

Figure 4 is a sectional view taken on the line 4—4 of Figure 2.

We claim:

The ornamental design for a fly swatter, as shown.

HERBERT JAHN.
CHESTER S. ZAREMBA.
